UNITED STATES PATENT OFFICE.

AXEL JOHNSON, OF OAKLAND, CALIFORNIA, ASSIGNOR TO AMERICAN CAN COMPANY,
A CORPORATION OF NEW JERSEY.

CAN-CLOSING MACHINE.

Application filed January 12, 1916. Serial No. 71,772.

To all whom it may concern:

Be it known that I, AXEL JOHNSON, a citizen of the United States, residing in Oakland, in the county of Alameda and 5 State of California, have invented a new and useful Improvement in Can-Closing Machines, of which the following is a specification.

The invention relates to improvements for 10 closing filled cans, in which substantially the following operations are performed: The cans are fed continuously, as distinguished from intermittently, to a seaming or closing station; can ends are successively fed 15 into position above such cans; the can is here disengaged from the feeding means and elevated to the closing instrumentality, which is ordinarily, in the case of the sanitary can, a rotary seaming head, said can 20 engaging and taking with it, in proper position on its upper end, the end which has been so fed into position; the can is then closed partly or permanently; it is then deposited at another place on the said continuously moving feeding means and conveyed to the desired point of delivery.

By such a mode of feeding and operation the sudden stopping and starting of the filled and unclosed cans is obviated, the 25 operation is smoother and more rapid, and the liability of spilling any of the contents of the cans is greatly lessened.

With such objects in view as well as other useful results which inhere in the apparatus, the invention consists in the parts and combinations thereof hereinafter set forth and claimed.

In order to make the invention more clearly understood I have shown in the accompanying drawings means for carrying the same into practical effect, without limiting by improvements, in their useful applications, to the particular construction which, for the purpose of example, I have illustrated. In said drawings:

Fig. 1 is a plan view, partly in horizontal section, of a can closing machine embodying the invention.

Fig. 2 is a perspective view of the upper portion of the can lifter or bottom plunger or chuck.

Fig. 3 is a plan view of the devices for tightening the can feeding or conveying chain.

Fig. 4 is a vertical sectional view, show-

ing the continuously moving feed chain in side elevation, most of the supporting frame elements being omitted.

Fig. 5 is a side elevation of a portion of said chain, on a larger scale (about one half of full size).

Fig. 6 is a plan view of the same.

Fig. 7 is an elevation partly in section, illustrating the feed chain adjusting means.

Fig. 8 is a vertical central section of the same.

Fig. 9 is a horizontal section on line IX-IX of Fig. 8.

Fig. 10 is a plan view of the can delivery end of the table, illustrating the can end feed control mechanism.

Fig. 11 is a perspective view of a part of said mechanism.

Fig. 12 is a vertical section on line XII-XII of Fig. 13.

Fig. 13 is a plan view of the can end feed mechanism on a larger scale.

Fig. 14 is an elevation of the lower part of the machine looking towards the delivery end, or right-hand end of Fig. 1.

Referring to the drawings, the main fixed framework of the machine is indicated at 1. The filled cans without tops are fed either by hand or automatically upon a rotating receiving and feed table 2. This table 85 overlaps the margin of a second rotating table 3, which may be called the can spacing table, and which is supported by a bracket 4 of the frame 1, the table 2 being rotated by suitable driving means. The cans are 90 deflected on to the spacing table at the desired point by an arm 15.

When the cans have traveled about one half a revolution of the table 3, they engage a second deflecting guide rail 20 which 95 projects outwardly from the main fixed table 21 of the machine and across the path of the moving cans. When the cans encounter the rail 20 their course is so deflected as to deliver them successively between the 100 arms of a rotating star wheel 22 which delivers the cans from the can spacing table 3 on to the main table 21. With the said star wheel is preferably combined a suitable topping device 26.

Suitable means are provided to guide the cans, such as rails 19, 20 and 54. 49' is a spring guide forming with one of the rails 54 a yielding throat into which the cans are thrust by the star wheel 22 and which 110

holds firm and steadies the cans as they are delivered from the star wheel, so that they are not jarred or their contents spilled as they enter between the rails 54.

- 5   Mounted near the ends of the main table 21 are two sprocket wheels, a drive sprocket 50 and a driven sprocket 51, which carry a sprocket chain 52. This chain which will be referred to as the feed chain, carries at 10 spaced intervals, a plurality of upwardly projecting can feed fingers 53 which engage the cans successively as they are delivered on to the table 21 by the star wheel 22 and which carry them along the table, between 15 guide rails 54 removably fixed thereon, to the seaming station.

The drive sprocket wheel 50 is fixed on a shaft 55 which extends vertically downward and carries near the lower end thereof a 20 driven sprocket wheel 56. This sprocket is driven by a sprocket chain 57 which extends rearwardly and around a sprocket pinion 58 on the vertical cam shaft 59 of the closing machine. The sprocket chain 57 25 is maintained at a proper working tension by means of an adjustable idler 57'. This idler cooperates, in adjustment, with the feed chain adjusting mechanism hereinafter described, to bring the cans to the proper 30 points at the time when the other mechanisms, which are actuated by the cam shaft 59, operate. The sprocket wheel 56 is supported by two bolts 60 which pass through two diametrically opposed concentric slots 35 61 in the hub 62 of the said sprocket wheel 56 and which are screwed into a collar 63 of a sleeve 64 which is keyed to the sprocket shaft 55. Extending horizontally through the hub 62 of this sprocket wheel are two 40 parallel adjusting screws 65 which abut two shoulders 66 in the sleeve 64. When it is desired to set the conveyer chain 52 backward or forward to accommodate cans of a larger or smaller diameter and to insure 45 a proper delivery of the same accurately under the seaming head, it is necessary to first loosen the two binding bolts 60. The two adjusting screws 65 may then be operated. For example, suppose that it is desired that 50 the conveyer chain 52 be set forward to accommodate cans of a smaller diameter. By first loosening the bolts 60 and then loosening the left hand screw (Fig. 9) and tightening the right hand one the sleeve 64 will 55 thereby be rotated counter clockwise and the shaft 55 being keyed thereto, will also be turned in the same direction relative to the sprocket 56. This will cause the conveyer chain drive sprocket 50 to turn in the same 60 direction causing the conveying limb of the chain 52 to be advanced. In adjusting the conveyer chain for cans of a larger diameter the operation is the reverse. When the conveyer chain has been moved the proper 65 distance to accommodate cans of a different

diameter, the two locking bolts 60 are tightened thereby binding the sprocket wheel 56 against the collar 63 of the sleeve 64 and causing them to again rotate as one.

In order that the exact distance that the 70 conveyer chain 52 should be moved for adjustment may be easily ascertained, there is provided on the outer face of the collar 63 of the sleeve 64 a graduated scale 67. Secured to the hub 62 of the sprocket wheel 75 56 is an indicator 68 which moves across the said scale when the adjusting screws 65 are operated.

The driven feed chain sprocket wheel 51 is fixed on a shaft 69 (Fig. 3) which is journaled in a bearing 70 located at one end of an arm 71 of a chain tightening lever 72. This lever is pivotally mounted at its center, as indicated at 73, upon the bracket 4 of the machine and below the feed table 21. 80 The other arm 74 of this lever bears against an adjusting screw 75 mounted in a lug 76 integral with the bracket 4. At the outer end of the sprocket bearing 70 is an arcuate slot 77 through which passes a cap screw 78. 90 This cap screw is threaded into the bracket 4 and locks the sprocket wheel bearing 70 to the bracket 4 after the tension of the chain has been regulated by means of the adjusting screw 75.

The sprocket wheel shaft 69 projects downwardly through an elongated aperture 79 in the bracket 4 and has keyed thereto at its lower end a gear wheel 80. This gear wheel meshes with and drives an idler pinion 100 81 mounted upon a shaft or pivot 81' at the under side of the bracket 4, which pinion meshes with a second idler 82 and the latter in turn drives a larger gear wheel 24 clamped to the hollow shaft 23 that carries 105 the star wheel 22 and the topper 26. The gear wheel 24 in turn drives a still larger gear wheel 83 clamped to the shaft 10 of the can spacing table 3. The movements of the table 3 and of the topping device heretofore 110 described are thus effected from the feed chain by this train of gearing.

Located about midway on the table 21, and in the path of the cans as they are advanced by the feed chain is a can lifter or bottom 115 plunger indicated as a whole at 84. The head 85 of this can lifter is slotted vertically as at 86, to permit the passage of the conveying chain 52 through the head and at the same time to allow the upward and downward movement of the head as it lifts the cans from the table to a seaming head 87. Secured to the base of the can lifting head 85 is a plunger rod 88 which is carried by a can lifter sleeve 89. Formed preferably integral with this sleeve and located about the middle thereof, is a housing 90 in which is arranged a compression spring 91 which yieldably supports the plunger rod 88. This spring is supported and its tension regulated 120 125 130

- by an adjusting screw 92 threaded into the lower part of the housing 90. Below the housing 90 the sleeve 89 continues downward and is vertically slidably mounted in a bearing 93 on a casing 94 (Fig. 14) secured to the framework 1 of the machine.
- In order that the downward action of the can lifter 84 will be of a steady and cushioned character there is provided a coiled spring 94' secured at its upper end to the can lifter casing 94 and at its lower end to a pin 95 fixed in the lower part of the sleeve 89. Journaled on the ends of a cross pin 96 fixed in a bearing 95' on the lower part of the sleeve 89 and below the housing 90 are a pair of links 96' which extend downwardly and to which are pivoted at 97 the arms of a can lifting yoke 99 at the front end of a lever 100. This lever extends rearwardly and is pivotally mounted at its middle by means of a pivot pin 101 on the casing 94 of the machine. It is necessary that the can lifter have an accurately timed extent of movement to take the unclosed cans from and re-deliver the closed cans to the feed chain, and there is provided a means of adjustment by the cross pin 96. The ends of this pin on which the links 96' are journaled are eccentric to its central portion which fits and can be turned in the bearing 95', and the height of the lifter can be regulated by turning said cross pin. The latter is held when adjusted by a tangential clamping screw 98.
- The innermost end of the lifting lever 100 is provided with a roller 102 which engages the track of a can lifter cam 103 fixed upon the vertical cam shaft 59 of the machine and which through the medium of said lever 100, links 96 and sleeve 89 actuates the can lifter head 85. The cam 103 is so shaped and timed in rotation as to move the can lifter 84 upwards the instant that a can has been deposited upon the head 85 of the same by the conveyer chain 52, in line with the seaming head.
- The forward and can engaging edge of the can feed fingers 53 is vertical near the base thereof as indicated at 104 and suitably shaped at its upper part to permit the cans to be retarded, without retardation of the conveyer, in their horizontal movement as they are disengaged from the chain conveyer. In the construction illustrated they are inclined rearwardly at the top as at 105. The can arrives upon the lifter and the latter begins to rise before the can is quite centered on the lifter but while the can is rising the vertical part of the finger continues to advance the can to centered position, and there leaves it when the can rises to the curved part 105, which inclines rearwardly to compensate or partly compensate for the continued advance of the chain. This construction gives a practical length of can engaging
- finger for certainty of operation, and the disengagement of the can is not so abrupt as to spill any of its contents, and its rate of advance is gradually diminished as it nears and arrives at the point where it is to stop 70 on the lifter.
- The top surface of the can lifter head 85 is provided with two lifter plates 106 and 107 having longitudinally knurled surfaces (Fig. 2). These plates overhang the conveyer chain slot 86 in the said head 85 leaving a space 109 between them wide enough to permit the passage of the fingers of the feed chain through the same. The knurled surfaces 108 of these plates tend to prevent 80 any twisting or rotary motion of the can body upon the can lifter head 85 while the can is being operated on by the rotary seaming head. The lifter head is provided with means for gradually, or without abruptness, 85 causing the can to come to rest on said head as it is lifted away from the finger 53. One suitable means for this purpose is the following: Pivotally mounted at one end as indicated, by a pin 110 upon the forward edge 90 of the front lifter plate 106, is a guide bar 111. This bar is yieldably held in an inward position towards the can by a leaf spring 112 secured to an arm 113 pivoted to the front of the lifter head 85 as at 114. The arm 113 and its spring 112 are normally held fast in an engaged position with the guide bar 111 by a cap screw 115 which passes through a slot 116 in the arm 113 and is threaded into the lifter head 85. The pivot of the guide 100 bar 111 consists in a downwardly projecting pin 110 which terminates in a head 118. This pin engages a slot 119 in the knurled base plate 106 and is prevented from upward displacement by the head 118 engaging the under side of the said plate. The outer and swinging end of the guide bar 111 is also prevented from any upward movement by a similar headed pin 120 which travels in an arcuate slot 121 in the plate 106 concentric with the pivot of the guide bar. It will be apparent that the guide bar 111 may be removed by simply loosening the cap screw 115, allowing the arm 113 and spring 112 to swing downward and out of engagement 105 with the pivoted guide bar 111. The guide bar may then be swung forward, disengaging the pin 120 from the arcuate slot 121, permitting the bar 111 and pivot pin 110 to be disengaged from the pivot slot 119. The inner wall of the guide bar 111 is undercut 118 as at 122 so as to engage the lower flange or seam of a can to prevent any upward movement of the can relative to the can lifter 84. Rigidly secured to the rear of the head 85 12 is a second fixed guide bar 123 having a similar undercut recess 124 which coacts with the recess 122 in holding the can down on the plates 106, 107. As the can is carried on to the can lifter 84 by the conveyer chain 52, 13

it forces the pivoted guide bar 111 outwardly against the pressure of the spring 112 and is thus held firmly, although not too tightly, upon the can lifter head 85, and gradually 5 brought to rest by frictional resistance without an abrupt stop. The can lifter head having previously commenced to rise, raises the can through a centering device to the seaming head, receiving in such movement an 10 automatically fed can end which is seamed in place by the seaming head, which will be later described.

The can now being closed the can lifter 84 descends lowering the closed can from the 15 seaming head again to the main feed table 21. As the can lifter is descending, but before the same has completed its stroke, the can is again engaged by a longer can extracting finger 125 fixed on the conveyer chain 20 52, and which projects upwardly through the space 109 between the base plates 106 and 107 and conveys the closed can off the lifter head and along the track to the delivering point on the table 21. These extracting 25 fingers 125 are comparatively straight and are located upon the conveyer chain 52 in the spaces between the curved can feeding fingers 53. It will be noticed that the cans are so spaced, and their movement so timed 30 before they are delivered upon the main feed table 21; that they are caught only by the curved conveying fingers 53, allowing the can extracting fingers 125 to pass the receiving point without having a can delivered before them. A can having been carried on to the lifter 84 by the conveying fingers 53 is raised, seamed and lowered in time to be caught by the extracting finger immediately 35 succeeding the conveying finger that delivered the can to the seaming station. By this arrangement there is always a space awaiting to receive a seamed can and the operation of the machine is very rapid.

The filled cans having been seamed and 40 closed and returned to the main table 21 are conveyed along the table by the extracting fingers 125 between guide rails 126 and 127 to the point where they are desired to be delivered. There are several such points on 45 the table where the closed cans may be so delivered. These points may be determined by the arrangement of the guide extensions or can-switching rails 128. They may be conveyed along the table and delivered at the 50 front of the machine at a point indicated by the letter A or they may be delivered at the end of the table at B. It is still possible that the location of the machine will make it desirable to have the cans continue around the 55 table between the guide rails 129 and 130 and be delivered from the machine at the rear of the same at the point indicated at C.

Any suitable can and seaming mechanism 60 may be combined to cooperate with the said can feeding devices. As illustrated (Fig. 4)

the seaming mechanism comprises a rotary seaming head 87 mounted to revolve on a vertical axis and located axially above the said can lifter 84. This seaming head may comprise first and second operation seaming 70 rolls 159, 159' which are caused to slide radially to perform the seaming operations by levers 172, 172' pivotally mounted on the seaming head. These levers are operated by cams 145, 145' fixed on a sleeve 144, and this 75 sleeve is reciprocated vertically by a yoke lever 204, the said lever being rocked at suitable times, preferably by mechanism connected with a vertical cam shaft 59 arranged at the rear of the machine. Arranged within 80 the seaming head is a vertically reciprocable knockout rod 149 for disengaging the seamed cans from the head. Also mounted in the seaming head to rotate therewith is an upper chuck 148 adapted to engage the can end 85 within the upwardly extending flange thereof and to form an abutment against which the seaming rolls may tightly compress the parts of the can seam.

With the parts above described may be 90 combined any suitable means for supplying can ends automatically to the open tops of the cans before they are operated on by the seaming head, the following being preferred: Secured at one end to the under side of the 95 seaming head casing 131 and extending outwardly therefrom and overhanging the main conveying table 21 of the machine, is a can end feed bracket 250. This bracket has a channel or track 251 machined in its upper 100 face which corresponds in shape in cross section to the cross section of a can end so that the top surface of a can end being conveyed along the said track will be flush with the surface of the bracket 250. The track 251 105 extends inwardly and terminates in a circular aperture 252 in the bracket 250 axially beneath the seaming head 87 and over the can lifter 84. The can end is deposited over this aperture by a feeding mechanism presently to be described, and there awaits the can body as it rises under the action of the can lifter 84, being of a larger diameter before seaming than the said aperture. Said 110 aperture forms a centering device for the can as it is elevated to the seaming head, being flared or beveled at the under side of the bracket, as shown at 252' (Fig. 4). Secured to the bracket 250 and above the track 251 is a casing or cover 253, which forms the 115 support for a can end stack holder 254, the latter being located above the outermost end of the track or channel 251. The casing 253, beneath the can end holder 254, has a circular aperture 254' therein to permit the can 120 ends to descend vertically from the holder 254 to the track 251 and into position to have the lowermost one separated from the stack 125 and conveyed along the said track to the centering device by two successive movements. 130

In the bracket 250 and substantially in the center of the track 251 is a longitudinal slot or passageway 255 which extends down through the bracket and the sides of which are horizontally recessed as at 256 and forms the supporting and guiding means for a reciprocating slide 257 the sides of which are so shaped as to engage within the horizontal recesses 256. The slide 257 is preferably formed in two parts, a lower and longer finger bar 258 and an upper and shorter carrier bar 259. Pivoted to the inner extremity of the finger bar 258 is a can end engaging finger 260 which extends upwardly above the surface of the track 251 and in the path of the can ends. This finger is normally held in its upward and engaging position by a leaf spring 261 which bears against an outwardly projecting lug 262 on the finger 260. The inner and can end engaging shoulder 264 of the carrier bar is provided with a steel fin 265 which extends inwardly slightly and projects over the can end when the latter is engaged and serves to some extent to assist in separating the lowermost one of the nested can ends from the stack prior to extracting it from beneath the stack and conveying it to the centering device.

30 Mounted upon the bracket 250 upon an eccentric adjusting pivot 266 and located at one side of the passageway 255, is a lever 267 one end of which carries a can end separating knife 268 while the other end thereof carries a roller 269 which bears against the edge of the carrier bar 259 and coacts with a recess 270 in the form of a cam or inclined surface 271, in the latter. The roller 269 is yieldably held against the side of the carrier bar 259 by a spring 272, one end of which is attached to the inner end of a lever 267 and the other end thereof secured to the bracket 250. It will be seen that when the slide 257 is moved to its outermost position the roller 269 under the action of the spring 272 will engage in the recess 270 in the carrier bar 259, allowing the separating knife 268 to move laterally from beneath the stack of nested can ends and permitting the same to descend and rest upon the track 251. When, however, the slide 257 commences to move inwardly along its guide-way, the cam surface 271 will engage the roller 269 and force the same out of the recess 270 until it bears against the straight side of the carrier bar 259. This outward movement of the roller 269 overcomes the spring 272 and turns the lever 267 about its pivot, causing the separating knife 268 to enter between the edges of the can ends in the stack and above the bottom one, cutting out the latter from its nested position and at the same time lifting the remainder of the stack and supporting the same clear of the carrier bar 259 as it con-

vey a single can end so separated along the track.

Secured to the under side of the seaming head casing 131 and extending outwardly therefrom is a can end feed lever bracket 324 terminating in a vertical bearing 325. Suspended beneath this bearing is a can end feed lever 326 which is supported by a stud shaft 327 which is integral therewith and which extends upwardly and is journaled in the said bearing 325 (Fig. 12). The can end feed lever 326 is preferably of inverted channel bar form and forms a housing 328 for a can end feed lever arm 329. This arm 329 is pivoted as indicated at 330 between the flanges of the housing 328. The lever arm 329 is normally held in raised position by a coiled spring 331 located near the inner or rear end of the lever arm. The upward movement of the outer extremity of said lever arm 329 is regulated by a set screw 332 in the lever arm housing 328. The lever arm 329 extends outwardly and beneath the can end feed bracket 250 and feed slide, engaging two pins 333 and 334 (Fig. 4) located on the under side of the finger bar 258 and which project downwardly therefrom upon each side of the lever arm 329. The forward pin 334 is slightly shorter than the rear pin 333 and is beveled as indicated at 335. It will be apparent that when the lever arm 329 moves forward towards the seaming station it will engage the shorter pin 334 thereby causing the slide 257 to move forward, and upon the backward movement of the said arm 329 the same will engage the longer pin 333 and cause the slide 257 to move rearwardly and into position to extract another can end from beneath the stack.

35 It will be apparent that as the slide 257 is reciprocated the shoulder 264 of the carrier bar 259 will extract the separated can end from beneath the stack and convey it along the track 251. The slide then returns and upon its next forward stroke the finger 260 of the finger bar 258 will remove the can end previously deposited on the track and carry it to the centering device where it is deposited over the aperture 252 and in a position to be engaged by a can body and seamed thereon. While the finger bar 258 has been removing the immediately disposed can end to the seaming head, the carrier bar 259 has extracted another can end from beneath the stack and deposited it on the track where it is waiting to be delivered to the seaming head by the finger bar. By this method there is a constant and successive feeding of can ends to the seaming station without the loss of time.

40 In order to prevent the can ends from riding backwards upon the finger bar 258 on the backward stroke of the same and

after the can end has been first deposited on the track, there is provided in the casing 253 a pin 336. This pin projects downwardly and has its lower end beveled as at 5 337. The upper end of the pin 336 engages a leaf spring 338, which serves to yieldably hold the said pin in its depressed and can end engaging position. As a can end is 10 conveyed forward by the carrier bar 259 it engages the beveled surface of said pin, forcing it upward and allowing the can end to pass beneath, but upon the rearward stroke of the carrier bar the can end engages the straight edge of the pin and is prevented 15 from moving rearwardly.

The wearing surfaces of the bearing 325 are protected by a tubular bushing 339 having at its upper extremity a collar 340 which forms a bearing surface for a lever 20 latch arm 341 which is mounted upon the upper end of the stud shaft 327. The lever 326 and its shaft 327 are supported in the bearing 325 by a washer 342, which is secured by a screw 343 to the upper end of 25 the stud shaft 327 and rests upon the latch arm 341. Pivoted to the outer end of the said latch arm 341 by a pivot pin 344 is an eccentric rod connection 345 into which is threaded an eccentric rod 346. The said 30 eccentric rod extends across the machine and is secured to an eccentric strap 347 which passes around an eccentric 348 fixed upon the vertical cam shaft 59. The arm 341 is connected with the lever 326 by a 35 latch 351 so as to operate the same.

Pivoted to the under side of the bracket 324 is a can end feed index lever 361 (Fig. 13) having a long arm 362 and a short arm 363 extending at substantially right angles 40 to each other. The arm 362 extends outwardly and over the lever arm housing 328 and is provided on its under side and at its outer end with a cam 364. This cam 45 engages a pin 365 projecting vertically from the lever arm 329 through an aperture 366 in the lever arm housing 328 and tends to normally depress the outer end of the said lever arm and hold the same out of engagement with the forward and shorter 50 pin 334 in the finger bar 258. Secured to the arm 363 of the said index lever 361 is a connecting rod 367 which extends across the machine beneath the seaming head casing 131, and which is held up in a horizontal position by a guiding support 367' attached to said casing.

Mounted upon the table 21 near the receiving end thereof and adjacent the path of the cans passing to the seaming station 60 is a bracket 368 in which is mounted a vertical stud shaft 369, which is integral with a can-controlled trip lever 370 which rests upon the table 21 and which projects across the path of the cans beneath the can guides 65 and which is actuated by the passing cans.

Adjustably mounted by means of a clamp bolt 371 upon the stud shaft 369 and below the bracket 368 is a vertical lever arm 372 which engages a notch 373 in an arm connection 374 to which is secured the end of 70 the connecting rod 367. It will be apparent that through this construction the lever arm 329 will normally oscillate to and fro without reciprocating the slide 257, but as soon as a can body passing along its track engages the 75 trip lever 370, it will force the same inward (Fig. 10) thereby throwing the vertical lever 372 about its pivot, causing the arm 362 of the cam lever 361, through the medium of the connecting rod 367, to be moved 80 from its engaging position above the pin 365 in the can end feed arm 329 (Fig. 13) allowing the same to rise under the action of the coiled spring 331 to its engaging position with the short pin 334 in the finger 85 bar 258, which can then be moved forward by the arm 329. When the arm reaches a point near the limit of its throw, the housing 328 will engage a set screw 375 mounted in a downward projecting lug 376 on the 90 under side of the can end feed lever 361, causing the latter to be rotated about its pivot and causing the longer arm 362 thereof to again be moved back to its normal position over the path of the pin 365. Now 95 when the can end feed lever arm 329 returns on its backward movement the pin 365 will engage under the cam 364 on the lever arm 362 causing the lever arm 329 to be depressed out of engagement with the shorter 100 pin 334 on the finger bar 258. The arm will continue to oscillate about its pivot (supposing the feeding of cans to be interrupted) being depressed each time when it reaches a point near the limit of its backward movement. This will continue without any actuation of the can end feed slide until another can actuates the can-controlled trip lever 370 causing the arm 362 and its cam 364 to be thrown out of the path of the 110 pin 365. It will be noticed that the lever arm 329 is not depressed low enough to prevent it from engaging the longer pin 333 on the finger bar 258, which pin is only 115 encountered by the lever arm 329 on its return or backward movement and which is designed only to return the slide 257 to its outward position. It will also be noticed that the can end feed mechanism is thrown 120 into operation by each individual can as it actuates the can-controlled lever and is thrown out of engagement as soon as a can end is fed to the seaming station; and if a can body is not in position to be closed, a can end will not be fed to the seaming station. 125

Power may be communicated to the cam shaft 59 by any suitable mechanism.

It will be seen that the rearwardly inclined or curved can-advancing fingers 53 130

of the continuously moving carrier 52, combined with the lifter 84 which moves the engaged part of the can, during its horizontal advance, vertically along said fingers 53, 5 constitute a means whereby the horizontal movement of the can is retarded but continued at diminishing speed. The top surface of the lifter frictionally resists the horizontal movement of the can and causes it to 10 hug the front face of said finger 53. This resistance is increased and the can steadied by the action of the guide bar 111, as described.

My invention does not exclude a construction and arrangement in which the continuously moving can feeding chain is depressed out of engagement with the can so as to leave the latter at the seaming station, and the seaming head is depressed by known 15 means so as to operate upon and seam the can without the necessity of elevating the latter; the can engaging portion of the chain being then raised from said depressed position so as to remove the seamed can.

20 By "seaming head" I include various can end attaching means. Such means may be a clincher which crimps the head loosely on to a can, all around the circumference or in spots. Also, when the seaming head is used, 25 only the first operation or curling roll may be put in operation, the complete hermetic seaming by the second operation being done by any suitable means after processing the filled and partly or loosely closed can; and 30 35 the words "closing machine" are not limited to a machine which hermetically closes the cans.

In Fig. 14 the parts 9, 10 and 17 relate to the can feeding and spacing mechanism; the 40 parts 23, 32, 35, 35', 36, 37, 37', 39, 40, 42, 43, 44, 45, and 46 relate to the topping mechanism; 36' is the extended base of the main frame 1; the parts 241, 242, 243, 244 and 245 relate to the mechanism for disengaging the 45 can from the seaming head; the parts 312 to 323 relate to the can marking mechanism; 420 is a coupling which unites the upper and lower parts of the shaft 59.

What is claimed is:

50 1. In a can seaming and closing machine, in combination: seaming mechanism; a continuously movable can-carrier arranged to deliver cans under and to convey them away from the said seaming mechanism, said carrier being provided with two sets of can-engaging means, one set for delivering the cans beneath the seaming mechanism and the other set for conveying the cans away from the said seaming mechanism; and a reciprocating can-feeding means cooperating transversely with the said carrier to transfer cans from said carrier to the seaming mechanism and from said seaming mechanism to the carrier.

65 2. In a can seaming and closing machine,

in combination: seaming mechanism; a continuously movable can-carrier arranged to deliver cans under and to convey them away from the said seaming mechanism, said carrier being provided with two sets of can-engaging means, one set for delivering the cans beneath the seaming mechanism and having backwardly inclined can engaging faces, and the other set for conveying the cans away from the said seaming mechanism; and a reciprocating can-feeding means cooperating transversely with the said carrier to transfer cans from said carrier to the seaming mechanism and from said seaming mechanism to the carrier. 70 75 80

3. In a can seaming and closing machine, in combination: a seaming mechanism; a continuously moving endless can-carrying chain arranged to deliver cans in line with and to convey them away from the said seaming mechanism and provided with means for holding the cans in spaced arrangement; and a reciprocating can feeding means cooperating transversely with the said chain to transfer cans from said chain 85 to the seaming mechanism and from said seaming mechanism to the chain.

4. In a can seaming and closing machine, in combination: a seaming mechanism; a continuously moving endless can-carrying chain arranged to deliver cans under and to convey them away from the said seaming mechanism and provided with means for holding the cans in spaced arrangement; can end feeding mechanism; a reciprocating 90 plunger co-operating transversely with the said chain to transfer cans from said chain to the seaming mechanism and from said seaming mechanism to the chain; and means cooperating with the said can-carrying chain actuated by the successive cans thereon and controlling the operation of the said can end feeding mechanism. 95 100 105

5. In a can seaming and closing machine, in combination: a seaming mechanism; a continuously moving endless can-carrying chain arranged to deliver cans in line with and to convey them away from the said seaming mechanism; and a reciprocating can feeding means cooperating transversely 110 with the said chain to transfer cans from said chain to the seaming mechanism and from said seaming mechanism to the chain; said chain being provided with two sets of can-engaging means, one set for delivering 115 the cans to said reciprocating can feeding means and the other set for receiving the seamed cans therefrom.

6. In a can seaming and closing machine, in combination: a continuously movable can 120 carrier; seaming mechanism; can engaging devices having inclined can-engaging faces moving uniformly with the carrier; and a can lifter for removing the can from its can engaging device; whereby the movement of 125 130

the can is continued at retarded speed on said lifter while it is being disengaged from said carrier.

7. In a can seaming and closing machine, 5 in combination: a continuously movable can carrier; a seaming mechanism; can holding and spacing means moving uniformly with the carrier and a cooperating can lifter having means whereby the movement of the 10 filled and open can is retarded relative to the movement of the carrier while it is still engaged by the said holding and spacing means.

8. In a can seaming and closing machine, 15 in combination: a continuously movable can carrier; a seaming mechanism; a reciprocating can feeding means cooperating transversely with the said can carrier to transfer cans from said carrier to the seaming mechanism and from the seaming mechanism to the carrier, and can-engaging and spacing means moving uniformly with the carrier adapted to disengage gradually from the can as the latter is moved away from the carrier; and 20 means whereby the movement of the can is retarded relative to the movement of the carrier.

9. In a can seaming and closing machine, 30 in combination: seaming mechanism; a continuously movable can carrier provided with means for holding the cans in spaced arrangement and which are constructed with means to permit the gradual disengagement of the cans successively as they come in line 35 with the seaming mechanism; means for retarding the movement of the cans relative to said carrier; a centering device; and means for disengaging the cans from the carrier and placing them in cooperative relation 40 with the centering device and the seaming mechanism.

10. In a can seaming and closing machine, 45 in combination: seaming mechanism; a continuously movable can carrier provided with means for holding the cans in spaced arrangement and adapted to permit the disengagement of the cans at the seaming station during the continued movement of the carrier; means for retarding the movement of 50 the cans during such disengagement; means for disengaging the cans from the carrier and placing them in cooperative relation with the seaming mechanism; can end feeding mechanism for delivering can ends in 55 the path of movement of the cans towards the seaming mechanism; and means whereby the cans while engaged by the carrier control the operation of said can end feeding mechanism.

60 11. In a can seaming and closing machine, in combination: a continuously movable can carrier arranged beneath the path of the cans; a seaming mechanism; a reciprocating can feeding means cooperating transversely 65 with the said can carrier to transfer cans

from said carrier to the seaming mechanism and from the seaming mechanism to the carrier; means on said carrier whereby, in cooperation with said reciprocating means, the carrier may gradually advance relative to 70 the can while propelling the same; a centering device in the path of the can while it is moved by the reciprocating can feeding means; can end feeding mechanism for delivering can ends in the path of the can as 75 it is moved towards the seaming mechanism; and means whereby the can while engaged by said can carrier controls the operation of the said can end feeding mechanism.

12. In a can seaming and closing machine, 80 in combination: a seaming station; a can carrier extending under and beyond said seaming station and provided with can engaging members; and means for vertically disengaging the can and the can engaging member before the seaming operation whereby a member of said carrier delivers a can to the seaming station and another member of said carrier removes said can from the seaming station.

13. A continuously moving conveyer having a plurality of continuously advancing can-engaging and spacing means; can end attaching means; and can-lifting mechanism which receives the cans and lifts them from 95 the said engaging means of the conveyer to said attaching means and after the operation thereof lowers them into the path of other of said engaging means of the conveyer.

14. In a machine for attaching can ends to can bodies, the combination of can end attaching means, a continuously moving can carrier having fingers with rearwardly inclined can-engaging faces for holding cans 105 in definite spaced arrangement, devices for transferring the cans from the said carrier to said attaching means, and actuating mechanism whereby the said carrier and transferring devices are operated in timed 110 relation to each other to disengage the cans from the said holding means and transfer them into operative relation with the said attaching means.

15. In a machine for operation on cans, 115 the combination of continuously moving mechanism having a plurality of spaced can-propelling devices for moving cans into said machine, operating mechanism into line with which the cans are so moved, means for first 120 retarding and then stopping the horizontal movement of the cans as they arrive in line with said operating mechanism, and means for receiving the cans from said continuously moving mechanism and acting to remove them from said propelling devices and present them to said operating mechanism, and after the operation of the latter acting to restore them into the path of other of 125 said propelling devices of the continuously 130

- moving mechanism, the latter acting to carry the cans out of the machine.
16. In a machine for attaching can ends to can bodies, the combination of can end attaching means, a continuously moving can carrier having means for holding cans in definite spaced arrangement, devices for transferring the cans from the said carrier to said attaching means, actuating mechanism whereby the said carrier and transferring devices are operated in timed relation to each other to disengage the cans from the said holding means and transfer them into operative relation with the said attaching means, and can-retarding means which yieldingly engage the cans as they arrive at the point of transfer, the said holding means of the carrier being constructed to permit such retarding of the cans.
17. In a machine for attaching can ends to can bodies, the combination of can end attaching means, a lifter for raising the cans relative to said attaching means, a continuously moving can carrier having means for holding cans in definite spaced arrangement and acting to place the cans successively over the said lifter, means for adjusting the carrier in its path to regulate the positions of the said holding means, and actuating mechanism whereby the said carrier and lifter are operated in timed relation to each other to disengage the cans from said holding means and lift them into operative relation with the said attaching means.
18. In a machine for attaching can ends to can bodies, the combination of can end attaching means, a lifter for raising the cans relative to said attaching means, a continuously moving endless chain can carrier having means for holding cans in definite spaced arrangement and acting to place the cans successively over the said lifter, and actuating mechanism whereby the said carrier and lifter are operated in timed relation to each other to disengage the cans from said holding means at a station and lift them into operative relation with the said attaching means, said carrier being arranged to re-engage the cans at the station where they were so disengaged.
19. In a can closing machine, the combination of a seaming mechanism, a continuously moving conveyer, having fixed can advancing members secured thereto for advancing open end cans continuously in spaced single file processional arrangement, and cooperating upwardly moving mechanism for removing each can from said conveyer as it reaches operative alignment with said seaming mechanism and assembling it with a can cover, and replacing the said can with its assembled cover onto said continuously moving conveyer, still spaced ahead of the next following open end can without interrupting the continuous forward movement of any of the advancing cans on said conveyer.
20. In a can closing machine, the combination of a seaming mechanism; a continuously moving conveyer, having positive can advancing means moving always at the same speed of said conveyer for advancing open end cans continuously in spaced single file processional arrangement, and cooperating upwardly moving mechanism for removing each can from said conveyer as it reaches operative alignment with said seaming mechanism and assembling it with a can cover, and replacing the said can with its assembled cover onto said continuously moving conveyer, still spaced ahead of the next following open end can without interrupting the continuous forward movement of any of the advancing cans on said conveyer.
21. In a can closing machine, the combination of a seaming mechanism, a continuously moving conveyer having alternate sets of conveying sections for advancing cans, one set of said conveying sections arranged for advancing open end cans in spaced single file processional arrangement to cooperating upwardly moving mechanism for removing each can from said conveying section as it reaches alignment with said seaming mechanism and placing it in contact with a positioned can cover, and moving the can and cover into operative relation with said seaming mechanism to secure the said cover to the said can and then returning the can with cover to the next advancing conveying section still spaced ahead of the next following open end can without interrupting the continuous forward movement of any of the advancing cans on said conveyer.
22. In a can closing machine, the combination of a seaming mechanism, a continuously moving conveyer having spaced can-propelling devices for advancing open end cans continuously in spaced single file processional arrangement, and cooperating upwardly moving mechanism for removing each can from out of the path of said spaced devices of said conveyer as it reaches operative alignment with said seaming mechanism and assembling it with a can cover, and replacing the said can with its assembled cover onto said continuously moving conveyer still spaced ahead of the next following open end can without interrupting the continuous forward movement of any of the advancing cans on said conveyer.
23. In a machine wherein filled cans are handled, an endless continuously traveling can-carrying belt having a plurality of can spacing and propelling means which are constructed to permit a continuous forward movement of the carrier relative to the can while the forward movement of the propelled can is retarded, in combination with

such can-retarding means and can-lifting means.

24. In a can seaming machine, the combination of a continuously operating conveyer provided with regularly spaced can-engaging lugs, means for delivering cans to alternate lugs only of said conveyer, means for removing a can from in front of one of said lugs and replacing it in front of the next succeeding lug, and means for operating upon said can while removed from said conveyer.

25. In a can seaming and closing machine, in combination: a seaming mechanism; a continuously moving can-carrier arranged to deliver cans under and to convey them away from the said seaming mechanism; and provided with means for holding the cans in spaced arrangement; and a reciprocating can-feeding means cooperating transversely with the said can carrier to transfer cans out of the path of said holding means of the carrier and to the seaming mechanism and from said seaming mechanism back to within the path of said holding means.

26. In a can seaming and closing machine, in combination: a seaming mechanism; a continuously moving can-carrier arranged to deliver cans in line with and to convey them away from the said seaming mechanism; and provided with means for holding the cans in spaced arrangement; and a reciprocating plunger cooperating with the said can carrier to transfer cans out of the path of said holding means of the carrier and to the seaming mechanism and from said seaming mechanism back to within the path of said holding means.

27. In a can seaming and closing machine, in combination: a rotary can end seaming head; a continuously moving can-carrier arranged to deliver cans in line with and to convey them away from the said seaming mechanism; and provided with means for holding the cans in spaced arrangement; and a reciprocating plunger cooperating with the said can carrier to transfer cans out of the path of said holding means of the carrier and to the seaming mechanism and from said seaming mechanism back to within the path of said holding means.

28. In a can seaming and closing machine, in combination: a seaming mechanism; an upper can holding chuck; a continuously moving can-carrier arranged to deliver cans under and to convey them away from the said seaming mechanism; and provided with means for holding the cans in spaced arrangement; and a lower reciprocating plunger or chuck cooperating with the said can carrier to transfer cans from within the path of said holding means of the carrier to the said upper chuck and seaming mecha-

nism, and thence back to within the path of 65 said holding means.

29. In a can seaming and closing machine, in combination: seaming mechanism; can-end feeding mechanism; a continuously movable can-carrier arranged to deliver cans 70 under and to convey them away from the said seaming mechanism; and provided with means for holding the cans in spaced arrangement; and a reciprocating can-feeding means cooperating transversely with the said 75 carrier to transfer cans out of the path of said holding means of the carrier and to the seaming mechanism and from said seaming mechanism back to within the path of said holding means.

30. The combination of a continuously moving conveyor having means for holding cans in spaced arrangement and adapted to convey cans in a given direction; can end attaching means; and upwardly moving 85 mechanism acting to remove cans successively from within the path of the holding means of said conveyor and into operative relation with the can end attaching means, and to return them in a reverse direction 90 and by the same path to within the sphere of operation of said holding means.

31. In a machine for attaching can ends to can bodies, the combination of can end attaching means, a continuously moving can 95 carrier having means for holding cans in definite spaced arrangement, devices for transferring the cans from said carrier to said attaching means, and actuating mechanism whereby the said carrier and transferring devices are operated in timed relation to each other to remove the cans from the path of said holding means at a station and transfer them into operative relation with said attaching means, said carrier being arranged to reengage the cans after attachment of their ends, at the same station where they were so removed.

32. In a can seaming and closing machine, in combination, seaming mechanism, can-end feeding means, a continuously movable can-carrier arranged to cause the cans to operate mechanism of said can end feeding means, and acting to deliver cans under and to convey them away from the said seaming 110 mechanism and provided with means for holding the cans in spaced arrangement, and a reciprocating can-feeding means cooperating transversely with the said carrier to transfer cans from within the sphere of operation 115 of said carrier to the seaming mechanism and from said seaming mechanism to within the sphere of operation of said carrier.

33. In a can seaming and closing machine, in combination, a seaming mechanism, can-end feeding mechanism, a continuously moving can-carrier arranged to deliver cans 125 in line with and to convey them away from

- the said seaming mechanism and provided with means for holding the cans in spaced arrangement, a reciprocating plunger cooperating with the said can carrier to transfer cans from within the sphere of operation of said carrier to the seaming mechanism and from said seaming mechanism to within the sphere of operation of the carrier, and means cooperating with the said can carrier, actuated by the continuously moving carrier through the media of the successive cans thereon and controlling the operation of the said can end feeding mechanism.
34. In a can seaming and closing machine, in combination, a seaming mechanism, a continuously moving can carrier arranged to deliver cans in line with and to convey them away from the said seaming mechanism, and provided with means for holding the cans in spaced arrangement, can-end feeding mechanism, a reciprocating plunger cooperating with the said can carrier to transfer cans from within the sphere of operation of said carrier to the seaming mechanism and from said seaming mechanism to within the sphere of operation of the carrier, and means cooperating with the said can carrier, actuated by the successive cans thereon and controlling the operation of the said can end feeding mechanism.
35. In a machine for attaching can ends to can bodies, the combination of can end attaching means, a continuously moving can carrier having means for holding cans in definite spaced arrangement, can end feeding means, devices for transferring the cans from the said carrier to said attaching means, actuating mechanism whereby the said carrier and transferring devices are operated in timed relation to each other to remove the cans from within the sphere of operation of said holding means and transfer them into operative relation with the said attaching means and then to return said cans to within the sphere of operation of said holding means, and means whereby a can while engaged by said can carrier controls the operation of the said can end feeding means.
36. In a machine for attaching can ends to can bodies, the combination of can end attaching means, a lifter for raising the cans relative to said attaching means, can end feeding means, a continuously moving can carrier having means for holding cans in definite spaced arrangement and acting to place the cans successively over the said lifter, actuating mechanism whereby the said carrier and lifter are operated in timed relation to each other to remove the cans from within the sphere of operation of said holding means and lift them into operative relation with the said attaching means and then to return said cans into the sphere of operation of said holding means, and means whereby a can while engaged by the said can carrier controls the operation of the said can end feeding means.

In testimony whereof I have affixed my signature hereto.

AXEL JOHNSON.
